UNITED STATES PATENT OFFICE.

GEORGE C. JOHNSTON, OF CUBA, ILLINOIS.

FOLDABLE HANGING SEAT.

1,217,950.

Specification of Letters Patent.

Patented Mar. 6, 1917.

Application filed November 10, 1915. Serial No. 60,710.

To all whom it may concern:

Be it known that I, GEORGE C. JOHNSTON, a citizen of the United States, residing at Cuba, in the county of Fulton and State of Illinois, have invented certain new and useful Improvements in Foldable Hanging Seats, of which the following is a specification.

This invention relates to the class of 10 chairs, and pertains especially to a folding or collapsible seat adapted to be temporarily suspended in seating position from various suitable objects, and to be removed from said position for folding and storing when 15 not in use.

The object of the invention is to provide a foldable seat construction specially adapted for children which shall be expeditiously unfolded into seating position, and 20 to furnish means for adjustably hanging the seat in position for occupancy, as from the back of a chair, the back of the front seat of an automobile, or for adjustably suspending the seat in seating position from 25 any other place or object to which the hanging means may be found applicable.

A further object of the invention is to provide a detachable tray or table of special construction which shall be adjustable on 30 the folding members of the seat, and to provide means for extending and bracing the seat in seating position.

Various other objects, advantages, and improved results are attainable in the practical application of the invention, as will be 35 hereinafter set forth.

In the accompanying drawings forming part of this application:—

Figure 1 is a perspective view showing 40 the application of the seat to the back of the front seat of an automobile.

Fig. 2 is a side elevation showing the seat applied to the back of an ordinary dining chair.

Fig. 3 is a side elevation showing the application of the extension rods.

Fig. 4 is an elevation showing the parts in folded position. Fig. 5 is a central sectional view.

Fig. 6 is an inverted perspective view of a tray arm.

Fig. 7 is a detail sectional view of the coupling and adjusting sleeve.

Fig. 8 is a perspective view of a modification of a tray arm.

The same reference characters denote the

same parts throughout the several views of the drawings.

The seating board 1 is preferably made of three-ply wood, but other suitable material may be used. The upper face of the board 1 is provided with two sets of eyes 2 adjacent to the side edges of the board, the purpose of the eyes will be hereinafter explained. The under face of the board 1 is 65 provided with a pair of sleeves 3 in each of which is adjustably secured, by thumb screws 4, an extension rod 5. The back edge of the board is provided with a suitable strip 1^a, such as felt or rubber, for 70 protecting the said edge and also any object it engages in hanging the seat.

The foldable elements of the seat consist of a pair of pivoted side frames and these frames being of the same shape and construction and performing the same functions, only one of them will be described in detail. The frames are preferably formed by one rod, or composed of a single piece of stiff wire of suitable size and 75 length, and one of said frames comprises a front member 6, a bottom member 7, which is pivoted in one set of the eyes 2, so that the bends or corners 8 prevent lengthwise movement of the member 7, a top member 85 9 parallel with the bottom member 7, and terminating in an upwardly turned end 10 and a rear member 11 parallel with the front member 6 and having an extension 12 projecting into engagement with and extending above the end 10, which is secured to the extension 12, by means of a special 90 clamp or coupling 13, having a projecting loop 14 for attaching a strap 15.

The adjustable hanger for the seat comprises a pair of hooks 16, having a hollow stem 17 slideable upon the extension 12, and 95 adjustably secured by thumb screws 18.

The tray or table 19, is preferably composed of three-ply wood, but other suitable material may be used. The tray has a pair 100 of arms 20, adapted to extend over the forward portion of the top members 9, and the under face of said arms is provided with a plate hook 21, for hooking over said members 9.

Referring to the modification shown in Fig. 8, the tray 22 has metal arms 23 attached thereto in lieu of the tray hooks 21, and said arms have a tubular portion 24, 110 provided with a slot 25, by means of which the portion 24 is sprung upon the members 9.

In applying the seat in hanging and seating position, the hooks 16 are hooked to the object, for example as shown in Figs. 1 and 2, and the height of the seat is adjusted as desired by operating the hook stems and their set screws. The hanging of the hooks will hold the frame members in upright position so that the seat is ready to be occupied with or without the tray or table which may be applied and adjusted as desired or as occasion may demand.

It will be understood that the seat may be used as a vehicle seat for adults as well as children, that it may be made in various sizes, that it may be hinged from various places, and that in the event of hanging the seat from an object which would permit the seat board to swing out of proper seating position the extension rods are employed for adjusting the seat to proper or desirable seating position.

Obviously when the parts are folded in flat position, the seat will occupy a very small space and may therefore be readily and conveniently stored or placed as desired, and in such folding the hanger hooks may be removed if desired.

I do not wish to be understood as confining my invention or the parts thereof to any particular size, material, or to the method of making the same, nor do I wish to limit myself in the practical application of my invention, but reserve the right to make such changes and alterations in manufacture and adaptability of the invention as may come within the scope of the appended claim.

Having thus described my invention what I claim as new and desire to secure by Letters Patent is:—

A foldable hanging chair comprising a seat having a concaved front edge and a convexed rear edge, a pair of side frames mounted on the seat, said frames having a vertically extending member and a short upturned member abutting against the vertical member, a fixed coupling inclosing the short member and having an aperture through which the vertical member extends, a strap loop projecting from the coupling, a tray having inwardly projecting arms extending over the top portion of the side frames, a plate secured lengthwise the arms and having a hook-shaped flange for engaging said frames, and means connected with the said vertical members for suspending the chair.

In witness whereof I hereunto set my hand in the presence of two witnesses.

GEO. C. JOHNSTON.
